UNITED STATES PATENT OFFICE.

EDWARD P. FOX, OF GARNER, IOWA.

SELF-LOADING EARTH-SCRAPER.

SPECIFICATION forming part of Letters Patent No. 534,257, dated February 19, 1895.

Application filed December 26, 1894. Serial No. 533,037. (No model.)

To all whom it may concern:

Be it known that I, EDWARD P. FOX, a citizen of the United States of America, residing at Garner, in the county of Hancock and State 5 of Iowa, have invented a new and useful Self-Loading Scraper, of which the following is a specification.

The object of this invention is to provide a scraper arranged to be moved either backwardly or forwardly by means of cables attached to opposite ends thereof and particularly adapted for use in dredging or digging ditches through marshes or other places where an operator cannot conveniently control its 15 movements, it being arranged so that it may be set to fill with earth when advanced and when full to automatically assume a position whereby it may be dragged over the ground surface to a point where it may be dumped.

20 My invention consists in certain details in the construction, arrangement and combination of a scraper and frame therefor whereby when the scraper is filled it will automatically assume a position parallel with the frame to 25 prevent it from entering the ground farther, as hereinafter set forth, pointed out in my claims and illustrated in the accompanying drawings, in which—

Figure 1 is a side elevation of the device 30 showing the scraper in position for loading and by dotted lines in position for carrying. Fig. 2 is a top or plan view of the same, and Fig. 3 is a longitudinal sectional view.

Referring to the accompanying drawings 35 the reference letter A is used to indicate the frame composed of a single piece of metal with straight parallel sides and its ends curved and bent upwardly. It is provided with the openings A² and A³ at its forward and rear 40 ends respectively adapted to admit cables whereby it may be drawn forwardly or backwardly over the ground surface.

The scraper proper B, may be of any ordinary contour and is provided with outwardly 45 projecting journals B² near its forward end admitted into the bearing boxes B³ fixed to the sides of the frame A. Its rear end C is hinged at C² to swing in a vertical plane and C³ indicates lugs formed on or fixed to the ends 50 of the part C near its top to project outwardly through the segmental slots D in the sides of

the scoop thus permitting a limited movement of the end piece C.

F indicates brackets fixed to the sides of the frame A and having its top surface inclined 55 upwardly and rearwardly and one or more recesses F² in their upper rear faces also having upwardly and rearwardly inclined bottom edges. These brackets are so positioned that the said lugs C³ may rest upon their tops or 60 enter one of the recesses when at the forward limit of their movement and clear the said brackets when at the rearward limit of their movement.

H indicates handles fixed to the sides of the 65 scrapers in the usual manner.

J indicates a contractile coil spring having its lower end fixed to a lug J² on the frame A and its upper end formed into a hook J³ adapted to be placed over one of the handles 70 H when the rear end of the scraper is elevated and normally exert a yielding pressure downwardly and arranged to be readily disengaged from the handle, when the scoop is in position for carrying.

In practical operation assuming that it is 75 desired to dig a ditch through wet ground and that cables were attached to the opposite ends of the frame A the lugs C³ are placed on top of the brackets (if it is desired to dig deep) or 80 in one of the recesses, and the cable at the front of the scoop advanced. It will be obvious that the scoop will be held in a position at an angle relative to the frame and the ground surface, as the frame constantly lies 85 parallel with the ground surface. Then when the scraper is full the earth will press against the rear end piece and move it backwardly thus releasing it from the bracket and allowing the rear end of the scraper to rest upon 90 the frame A and thereby be carried over the ground surface on said frame. It may be dumped in the ordinary manner by grasping the handles and turning the scraper over after disengaging from the handles, the hook at 95 the top of the spring.

Having thus described my invention, what I claim as new therein, and desire to secure by Letters Patent of the United States therefor, is—

1. An improved scraper, comprising an oblong frame curved upwardly at its ends, a

scraper pivoted near its forward end to the sides of said frame, a device in the rear end of the scraper adapted to move longitudinally thereof when pressed upon by earth in the 5 scraper, means for holding the rear end of the scraper elevated relative to the frame and means for releasing the rear end of the scraper when said movable device in the rear of the scraper is pressed backwardly, for the purposes stated.

2. An improved scraper, comprising an oblong frame curved upwardly at both ends, a scraper pivoted near its forward end to the sides of the frame and having slots in its sides 15 near its rear end, a rear end piece for said

scraper hinged at its lower edge and having two lugs near its top to project outwardly through the said slots, handles on the rear end of the scraper, a contractile coil spring fixed to the frame and detachably connected with one of the handles and two brackets fixed to the frame to engage said lugs when they are moved forwardly and support the scraper until the rear end is forced backwardly and the lugs thereby disengaged from said brackets 25 substantially as and for the purposes stated.

EDWARD P. FOX.
